UNITED STATES PATENT OFFICE.

ALANSON WOOLSEY, OF ADRIAN, MICHIGAN.

ROAD-SCRAPER.

SPECIFICATION forming part of Letters Patent No. 267,815, dated November 21, 1882.

Application filed July 5, 1882. (No model.)

To all whom it may concern:

Be it known that I, ALANSON WOOLSEY, of Adrian, in the county of Lenawee and State of Michigan, have invented new and useful Improvements in Road-Scrapers; and I do hereby declare that the following is a full, clear, and exact description thereof, reference being had to the accompanying drawings, which form a part of this specification.

10 The nature of this invention relates to certain new and useful improvements in the construction of road-scrapers; and the invention consists in the peculiar construction, arrangement, and combination of the various parts, all as more fully hereinafter set forth.

Figure 1 is a side elevation of my improved scraper. Fig. 2 is a longitudinal section on the line L L, Fig. 1.

In the accompanying drawings is represented an ordinary wagon, which is provided with the bed E, which rests and is secured in any proper manner upon the bolsters of the wagon.

25 A represents the scraper, which is provided with the vertical posts C D, which project up through the bed, and it is also provided with any proper shoe, S, upon its front lower edge.

20 i i' represent draft-chains, one end of each of which is secured to the head of the scraper A, while the opposite or forward ends are secured to a V-shaped clevis, k, which engages with the king-bolt l.

30 B represents a spreader-bar, the outer end of which is provided with a clevis, j, through which the chain i' passes, while the opposite end passes through the head of the scraper A,

beneath the plate P, and is provided with a series of holes, V, through one of which a pin may be inserted, so as to retain the bar B in its proper position. By the adjustment of this bar B, in connection with the chains i i', 40 the angle of the scraper A can readily be determined.

45 f are chains which lead from the top of the scraper to a windlass, H, properly mounted upon the wagon, and is operated by suitable levers, h, for raising and lowering the scraper, as the work to be performed shall require, or so that the scraper will entirely clear the road.

50 While I show and describe a windlass for raising the scraper, I do not wish to be confined to such construction, as there are various ways for producing the desired result which could be employed without departing from the spirit of my invention.

55 By this construction and arrangement of parts I produce a scraper which can readily be attached to a common wagon and advantageously be employed in "working roads."

What I claim as my invention is—

60 A road-scraper consisting of the scraper A, spreader-bar B, posts C D, chains i i', and chains f, in combination with a wagon provided with proper means for raising and lowering the scraper, substantially as and for the purposes set forth.

ALANSON WOOLSEY.
